UNITED STATES PATENT OFFICE.

JAMES J. SMITH, OF GLENSIDE, PENNSYLVANIA.

PICKER-STICK CLAMP.

Application filed May 6, 1927. Serial No. 189,404

The present invention relates to clamping devices, and more particularly to a clamp for maintaining the desired assembled relation between a picker stick of a power loom 5 and the support for the stick operating lever.

Some of the objects of the present invention are to provide an improved clamping device for loom picker sticks; to provide a positive means for locating the support of a 10 picker stick lever in a fixed position; to provide an improved picker stick clamp which will give the full range of adjustment without causing displacement of any of the parts under operating conditions; to provide 15 means for clamping a device to a picker stick and also to a lever hold-up strap hanger; and to provide other improvements as will hereinafter appear.

In the accompanying drawings Fig. 1 20 represents a side elevation of a part of a loom picker stick equipped with a clamp embodying one form of the present invention; Fig. 2 represents an edge elevation of that portion of the stick having the clamp 25 thereon; Fig. 3 represents a section on line 3—3 of Fig. 1; Fig. 4 represents a strap supporting piece; and Fig. 5 represents a detail of one part of the clamping device.

Referring to the drawings, one form of the 30 present invention is shown in Fig. 1 in assembled condition upon a loom picker stick 10 which is pivotally mounted at 11 and returned to its initial position by a spring 12. The picker stick operating lever, 13, which 35 is controlled by the picker cams, terminates in the usual hold-up strap 14, and is held in adjusted position upon the picker stick 10 by an adjustably mounted supporting hanger 15. This hanger 15 is preferably provided 40 with notches 16 at opposite sides thereof and an axially disposed extension 17. The notches 16 serve to seat the strap 14 as it passes about the hanger 15 and thus holds the strap 14, with its attached lever 13, at 45 the desired level.

For the purpose of attaching the hanger to the picker stick 10 so that it is held rigidly against displacement, a clevis clamp 20 is provided, the body part 21 of which fits 50 snugly about the hanger extension 17 while

its legs 22 straddle the picker stick 10 and terminate in threaded ends 23 projecting beyond the edge of the picker stick 10. A clamping plate 24 is apertured to fit over the ends 23 and seat flush against the edge of 55 the picker stick 10 where it is held fast by nuts 25 acting through locking spring washers 26.

For ensuring a rigid clamping of the hanger 15, the sides of the clevis clamp 20 60 are respectively provided with oppositely aligned slots 27 which respectively seat tongues 28 offset from the sides of a clamping block 30. The slots 27 have sufficient length to allow free unrestricted movement of the block tongues 28 so that the block 30 can automatically adjust itself for 65 different widths of picker sticks and thus always take a clamping position against the extension 17.

In order to overcome any tendency of the hold-up strap 14 to swing sidewise, the end of the body of the clevis 20 is provided with an elongated anchoring abutment 31 which is formed by stamping a portion of the material inward so that it will bite into the hanger extension 17 and hold the parts 75 against lateral relative movement.

In assembled condition the clamp 20 fits about the hanger extension 17 and also about 80 the picker stick 10 with the block 30 interposed between the stick 10 and the hanger 15. Thus when the nuts 25 are drawn up to make the plate 24 effective, there is a positive clamping of the hanger 15, the block 30 85 and the picker stick 10 with no chance of one becoming loose with respect to the other.

While only a single form is shown in which this invention may be embodied, it is to be understood that the invention is not 90 limited to any specific construction, but might be applied to various forms without departing from the spirit of the invention or the scope of the appended claim.

Having thus described my invention, I 95 claim:

A picker stick clamping device comprising a hanger provided with oppositely disposed notches to receive a hold up strap, an ex- 100 tension at one end of said hanger, a clevis

clamp arranged to fit about said extension and a juxtaposed picker stick, said clamp having slots formed in its legs to overlap both said stick and said extension in assembled condition, a plate arranged between said extension and stick and having tongues respectively slidably mounted in said slots,

and clamping devices for rigidly holding said clevis clamping said stick, said extension and said plate together.

Signed at Philadelphia, county of Philadelphia, State of Pennsylvania, this 6th day of April, 1927.

JAMES J. SMITH.
